US00D905844S

(12) **United States Design Patent** (10) **Patent No.:** **US D905,844 S**
(45) **Date of Patent:** **** Dec. 22, 2020**

(54) **FRAME OF HEAT DISSIPATION FAN**

(71) Applicant: **ENERMAX TECHNOLOGY CORPORATION**, Taoyuan (TW)

(72) Inventor: **Yen-Wen Su**, Taoyuan (TW)

(73) Assignee: **ENERMAX TECHNOLOGY CORPORATION**, Taoyuan (TW)

(**) Term: **15 Years**

(21) Appl. No.: **29/668,648**

(22) Filed: **Oct. 31, 2018**

(51) **LOC (12) Cl.** **23-04**

(52) **U.S. Cl.**

USPC **D23/411**

(58) **Field of Classification Search**

USPC D23/370, 376, 383, 377, 411, 414;
D13/179

CPC ... F04D 29/668; F04D 25/0613; F04D 25/082

(57) **CLAIM**

The ornamental design for a frame of heat dissipation fan, as shown and described.

DESCRIPTION

FIG. 1 is a perspective view of a frame of heat dissipation fan showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent unclaimed subject matter and form no part of the claimed design.
